STACK FRONT CLAMPING SYSTEM FOR AUTOMATIC CUTTING MACHINES

Carl Thumim, Lombard, Ill., assignor to Miehle-Goss-Dexter, Inc., Chicago, Ill., a corporation of Delaware
Original application Nov. 7, 1956, Ser. No. 620,928, now Patent No. 3,033,067, dated May 8, 1962. Divided and this application May 2, 1962, Ser. No. 191,991
2 Claims. (Cl. 83—282)

This invention relates generally to automatic cutting machines, and more particularly to novel advantageous clamping mechanism associated with a reciprocal knife assembly for executing transverse cuts on a stack of paper sheets fed therethrough intermittently. This patent application is a division of my copending case Serial No. 620,928 filed on November 7, 1956, now Patent No. 3,033,067 and assigned to the assignee hereof.

In a cutting machine of the type herein, a stack of paper sheets is supported on a horizontal table. A reciprocal knife blade is provided at the front end of the machine to execute transverse cuts on the paper stack in a predetermined manner. Reference is made to Patent No. 2,570,873 as typical of such type of machine. The novel clamp hereof holds the paper stack intact. It is arranged adjacent the knife blade, to act upon the stack as it is being transversely cut. A back gauge is provided at the rear end of the stack, movable towards the front, along the table on which the stack is supported. The back gauge is moved in a predetermined manner to push the stack forward between cutting operations of the knife. A start-stop program device is generally related with the back gauge to automatically start its movement and stop it at predetermined positions during the cutting cycles of the knife assembly.

It has been found in the operation of cutting machines that the stack of sheets often shifts or otherwise distorts its vertical alignment necessary to provide accurate transverse cutting of each sheet along predetermined positions. It is to be understood that when a cutting machine is used to sever pages of a book printed multiply on a long sheet (or advertising matters; or soap wrappers, etc.) it is necessary to sever the individually printed units at their exact predetermined borders. Also, where printing frames effect small unprinted areas between the printed wrappers or pages, "trim-out" cutting is needed to end up with the cleanly cut, accurately sized pages or wrappers, etc. Since identical multiple printed long sheets are arranged in a pile or stack, the imprints of the wrappers, pages, etc. must all be perfectly aligned and stacked in the up and down or vertical relation in order that the transverse cuts by the reciprocal knife be effected on each border of each printed unit, as is understood by those skilled in the art.

Pushing of the stack of sheets along the work table by the back gauge often causes the stack to "walk," i.e., to distort its vertical alignment of identically printed material. In other words, the forward edge of the stack shifts out of a vertical plane into an angular plane. It is readily apparent that such "walking" or shifting of the stack of sheets will result in the cutting of intermediate sheets at erroneous positions. Thus, non-registration of cutting will result on sheets in the stack. Consequently, it has been the practice of operators of a cutting machine to readjust the alignment of the stack at practically every cutting. Also, the front clamp at the knife blade that heretofore held the front edge of the stack firmly during cutting also often distorted the stack alignment.

Repositioning of the stack by the operator manually, of course, slows down the overall output or production by the machine. It is also hazardous for an operator to adjust the stack at the knife or front end of the machine

2

despite any safety precautions. In an effort to maintain production output, operators often by-pass the safety devices and carelessly believe that they can "beat" the machine. Severed fingers have resulted in unfortunate instances.

It is an important object of the present invention to provide full automaticity to a cutting machine for stacks or piles of sheets whereby it is unnecessary for an operator to adjust the stack during the whole cutting program thereon. "Walking" and other distortion of the piled sheets constituting the stack are eliminated by features of the invention herein to be set forth in detail hereinafter. Cutting of stacks of sheets of the present invention is performed exactly as programmed on a start-stop basis with no need for interruption of the program. The result is maximum production output without any hazardous interludes.

The knife clamping mechanism hereof is arranged close to and parallel with the knife bar of the transverse reciprocal cutting assembly. The knife clamp is pressed firmly onto the sheet stack just prior to the cutting operation, and holds the forward section of the stack intact. The clamping system of the invention is preferably hydraulically actuated, and comprises a torsion bar arranged to maintain the clamp level with the stack to a high degree of precision throughout its stack clamping operation. Thus the stack is pressed uniformly across its front clamped region, and cut cleanly and true.

The aforesaid and further features, advantages and objects of the invention will become more apparent from the following description of an exemplary embodiment thereof, illustrated in the drawings, in which:

FIGURE 1 is a side elevational view of a whole cutting machine embodying the invention front knife clamp, with the central portion of the machine broken away.

FIGURE 2 is an end elevational view of the cutting machine of FIGURE 1 at the front or "feed-out" position.

FIGURE 3 is an elevational view of the exemplary front clamp assembly.

FIGURE 4 is a top view of the clamp assembly of FIGURE 3.

FIGURE 5 is a cross-sectional view through the clamp assembly of FIGURE 3 taken along the line 5—5, as seen in the direction of the arrows.

FIGURE 6 is an end elevational view of the clamp assembly of FIGURE 3, as seen from the right end thereof.

FIGURES 1 and 2 show the side and "front" end elevations, respectively, of the cutting machine. The "front" end, as is normally termed in such commercial machines, will be herein also termed the "feed-out" position, corresponding to the position on the right end of the machine seen in FIGURE 1, and as seen in elevation in FIGURE 2. The front portion of the stack of sheets, after being cut off, is fed out from the "feed-out" end.

The main column 100 of the machine supports the guide supports for the knife cutting assembly, as well as the frame section of the balance of the machine, including the work table. The left side column 101 is an additional support for the machine and includes the circuit and relay panel for the electrical control system herein (not shown). Main column 100 serves also as an oil reservoir for the hydraulic servo components of the machine. The work table of the machine is arranged at a small angle to the horizontal plane, the left side of the table as viewed from feed-out end of FIGURE 2 being raised above the right end, as shown in the parent case.

A side gauge 102 is at the right side of the work table (FIGURE 2); the corresponding longitudinal side of the stacks of sheets rests against side gauge 102. Side gauge 102 is perpendicular to the tilted work table. A conveyor system 103 starts at tilted roller 104 adjacent the cutting

position under knife assembly 105 and extends to horizontal roller 106. An idler roller 107 completes the circuit of the conveyor sheet 108.

A hood 110 is mounted above conveyor 103, covering up the external access to knife assembly 105 for safety purposes. Hood 110 is hinged at 111, providing a suitable protecting means with ready accessibility to the cutting position at the "feed-out" end of the machine. A frame 112 extends from the main column 100 and serves to support conveyor assembly 103.

The cutting knife assembly 105 is shown in dotted lines, within the machine, in FIGURES 1 and 2. The general outline and correlation of the basic components of cutting mechanism 105 as seen in these figures is as follows: The knife bar 115 is supported in suitable guides and carries the knife blade 116 at its lower cut-out section. Knife assembly 115, 116 is arranged at the angle with horizontal to coact normally with the work bed and stack carried at the same angle. Knife blade 116 is demountable from knife bar 115 for replacement or sharpening.

A front or knife clamp 117 is arranged contiguous to and behind knife bar 115. Suitable control means are operated on clamp 117 to press it down on the front sector of a stack of sheets in the machine just prior to cutting by knife blade 116. The stack of sheets is held firmly adjacent the transverse cutting position wherein the reciprocable knife blade 116 effects the transverse cut, as is understood by those skilled in the art. A suitable torsion bar 118 and hydraulic cylinder 119 are associated with the clamp 117 for its motivation; as more fully set forth hereinafter. The exemplary knife assembly 105 is in the class known as guillotine cutters.

The back gauge 120 traverses the machine along its full operating length in the longitudinal direction. Back gauge 120 incorporates a vertical frame 121 that pushes the end of the stack of sheets on the work table forward to cutting blade 116. The back gauge 120 incorporates a series of fingers 122 of the back gauge clamp. The fingers 122 of the back gauge clamp are seen in progression in FIGURE 1 in view of the tilt of the back gauge with the horizontal. Their function is to press against the top layer of the back end of the stack of sheets in the cutting machine and firmly grip the whole back end of the stack or stacks throughout the cycles of the cutting program.

It is thus practical to arrange the loading of the stacks from the side of the machine at 125 (FIGURE 1). This is more efficient in production as the stacks or piles to be cut into book pages or wrappers, etc. are long, such as 40" to 60". These stacks are slid along the horizontal side table 126 and across to the work bed of the machine all from the machine side 125. The operator and the controls for the machine are arranged at side 125 for the progress of the cutting program on the sheets. Control panel 127 contains the start 128 and stop 129 control switches for operating the pump of the hydraulic system.

Electrical panel 130 contains the switches for controlling the operation of the back gauge with control button 131 for the forward movement, control button 132 for the reverse movement, and control button 133 for stop. These controls in panel 130 are manual over-rides by the operator for the action of the back gauge independent of the automatic programming of the machine operation. Similarly, there are two over-riding controls for the action of knife assembly 105; electrical control 134 arranged at the left side of the machine and control 135 at the right side of the operating position. Either one of these switches 134, 135 over-rides the automatic programming action of the knife assembly 105 whereby the operator can actuate knife blade 116 into cutting whenever desired. Similarly, a pedal for operating the hydraulic action of the back gauge clamp is arranged at 136, and pedal for operator actuation of the front clamp 117 at 137.

A safety hood 140 is provided over the work bed, the work thereon, and the back gauge 120. Hood 140 has a handle 141 to lift it out of the way when loading, un-

loading or otherwise by the operator. A safety switch (not shown) is actuated upon opening of hood 140, whereby all elements of the cutting machine are stopped from forward movement or actuation. This safety feature is important to the operator. A large panel of glass or Plexiglas may be arranged in hood 140 which is otherwise of sheet metal.

The front clamp 117 is situated behind knife assembly 105 and is operated by hydraulic cylinder 119 to press it down upon the front portion of the stack of sheets to be cut by blade 116. FIGURES 3 to 6 are enlarged detailed illustrations of front clamp assembly 117. It is important to operate the base section 380 of the bottom of clamp 117 in a level relation with respect to the stack. The clamp 117 is mounted transversely across the work bed of the cutting machine in a position to firmly clamp the stack of sheets to be cut by knife blade 116.

A torque bar 118 is provided with arms 381 to maintain the clamp 117 parallel with the stack to a predetermined high degree. With full pressure on hydraulic cylinder 119 to actuate clamp 117, and a narrow stack on only one side under the clamp base 380, the free side of clamp 117 can deflect only a small amount, say $\frac{1}{16}$ of an inch with the invention system. In other words, the torque device of the present invention limits the amount of unlevelling of the clamp base 380 on the stack or at the free side to only a small amount, as $\frac{1}{16}$ along a stack of commercial width. Thus, only a small amount of misalignment is permitted, not sufficient to prevent even a narrow pile of papers to be pressed down evenly for cutting.

The torque bar 118 extends across the bed of the machine, parallel to the base 380 of clamp 117. Bar 118 is suitably trunnioned to the frame of the cutting machine. A pair of arms 381, 381 extends from torque bar 118. A clevis 382 extends from each arm 381 to support a roller 383 at pin 384. A frame recess that coacts with vertical roller 383, 383 on each side of clamp 117 is provided through plates 385, 386 secured together by bolts 387 and vertical plates 388. The arms 381, 381 serves as levers to connect the torque shaft or bar 118 to the clamp 117 through the rollers 383, 383.

When the clamp 117 is actuated by the hydraulic cylinder 119 in the downward direction against a stack of sheets on the work bed of the machine, the clamp 117 is maintained in a vertical plane through the guide bars 395, 395 in guides heretofore described. Base 380 of clamp 117 is maintained in a predetermined relationship parallel to the work bed and stack through the torque rollers described herein. Cross-sectional FIGURE 5 is taken along the line 5-5 through FIGURE 3. Shown in dotted line, is the lower position of the clamp 117 with its arm at 381' and roller 383' coacting with the downwardly moved clamp 117. The torque bar 118 remains in its fixed position, and it will now be understood that clamp 117 maintains its predetermined degree of alignment through this means.

A narrow stack is thereupon also pressed down evenly, in any location across the work bed of the machine, despite the fact that a single hydraulic cylinder 119 located in the central portion of the clamp 117 is used. A feature for guiding oil that normally leaks from cylinder 119 across the piston 119a is provided in the clamp 117. The oil is troughed in a frame 390, and a drainage opening 391 is at frame 390. Thus, any oil leaking around cylinder 119 or piston 119a is guided into drain 391 and on through a tube 392 to the end 393 opening at clamp guide bar 395. The open end 393 of the tube 392 is adjacent a wider opening 396 in the guide bar 395. Thus, oil leaking through tube 392 from cylinder 119 is guided to a guide bar 395 where it runs down into the oil sump in the main casting. This feature prevents oil leakage on the stack of sheets operated upon.

The "level" alignment stated for the front clamp 117, and the illustration of clamp 117 in FIGURE 3 as hori-

zontal, is for illustration clarity. The invention "front" (knife) clamping system (117) may be utilized in cutting machines with the work table or stack workbed horizontal. The cutting machine 100 of FIGURES 1 and 2 has a work bed substantially inclined to the horizontal, as set forth hereinabove, and shown in detail in the parent case aforesaid. In such arrangement the knife mechanism 105 and the front clamp assembly 117 are mounted inclined to the horizontal in the same degree as the bed, as indicated in end view, FIGURE 2.

The pressure base 380 of clamp 117 is thereupon oriented to be parallel to the inclined work bed and to the sheet stacks to be operated upon, namely inclined to the horizontal in the machine construction. The wide clamp 117 extends across the whole work bed of the cutting machine 117, and is effectively "level" with the stack being clamped, regardless of its width or position across the bed when being cut. The invention clamping system 117 maintains the predetermined built-in angular orientation of the clamp base 380, and insures "level" clamping and smooth true stack cutting by the blade 116 even in machines with an inclined work bed.

Although this invention has been illustrated in an exemplary form, it is to be understood that modifications thereof are feasible within the broader spirit and scope 25 of the appended claims.

The embodiments of the invention in which an exclusive privilege or property is claimed are defined as follows:

1. In a machine of the character described for successively cutting a stack of sheets transversely across a 30

work table supporting the stack, a frame, a reciprocable knife system with a blade arranged transverse of the table for successively cutting forward portions of the stack when projected into the knife system, a clamp mounted on said table adjacent said knife system and, means for successively actuating said clamp to grip firmly the forward stack portion during cutting cycles thereof by said blade including mechanism for maintaining said clamp predeterminedly parallel to said work table and stack of sheets during its stack gripping phase, said mechanism comprising a torque bar carried parallel to said clamp and trunnioned to said frame, spaced arms rigidly secured to said bar and having freely rotative rollers at respective free ends, said clamp having respective recesses for said rollers, each recess having a top plate against which the respective roller engages for effecting leveling forces on said clamp to maintain substantial parallelism with said table.

2. In a machine as set forth in claim 1, the top plates of said recesses being separate removable pieces.
